UNITED STATES PATENT OFFICE.

JOSE G. BOUFFARTIQUE, OF HABANA, CUBA.

SAFETY STOPPER.

Application filed February 2, 1925, Serial No. 6,465, and in Cuba August 3, 1924. Renewed December 28, 1928.

This invention relates to a safety stopper and to a container with which the stopper is used, whereby, after having once extracted the original contents from the container, the 5 same cannot be subsequently refilled in its original form. It is applicable to all forms and sizes of containers and insures the origin of the contents.

A further object is to simplify the construction of devices of this character, reduce the 10 cost of their manufacture, and increase their efficiency.

One physical embodiment of the invention is shown, by way of example, in the accompanying drawings, wherein;

Fig. 1 is a view of the device, in elevation; Fig. 2 is a section on line 2—2 of Fig. 3; Fig. 3 is a section on line 3—3 of Fig. 2; Fig. 4 is a plan view of a detail; and

20 Fig. 5 is an elevational view of the detail of Fig. 4.

As shown in the drawing, a container 1, of any desired size and form, has a neck 2 receiving a stopper 3. The neck 2 has an extension 4, at the base of which is a groove 5 and an inner diamond cut 5', whereby to facilitate breaking the extension 4 off of the neck 2, by means of a blow on neck 6 carried by the extension. On the rim of the extension 30 4 is formed an internal undercut flange 7.

A cap 8, as shown in Fig. 2, is formed to fit closely over the rim of extension 4 and carries an internal undercut flange 9, similar to flange 7.

35 A segmental stopper is provided, formed of segmental pieces 10, of glass or other material, fitting over a resilient plug 11 as of rubber or cork, as shown in Figs. 4 and 5. The pieces 10, when in position around the plug

11, present flanges 12 and 13 for snapping 40 over flanges 7 and 9 in the extension 4 and cap 8, respectively.

Operation of the device is as follows:

Container 1 is filled with its contents, and stopper 3 is inserted.

The segmental stopper is then assembled as in Fig. 5, the plug 11 having first been treated if necessary, as by boiling or soaking to make it resilient, and is then forced into cap 8, past inclines 9', until flange 13 is received beneath flange 9. Cap 8 is then pushed over the rim of extension 4 until the stopper flange 12 is forced past inclines 7' and snaps under the extension flange 7. Thus, as shown in Fig. 2, container 1 is securely sealed, and can only be 55 unsealed by breaking off extension 4 along groove 5 and diamond cut 5'. Refilling of the container in its original form is thus made impossible.

Advertising matter of various description, 60 can be carried by the outer portion of extension 4, if desired.

Having described one form of my invention, I now claim;

In a device of the character described, a container, a neck on the container, a plug in the neck, an extension on the neck projecting beyond the plug, an internal, undercut flange at the outer end of the extension, a cap for fitting over the end of the extension, an internal 65 undercut flange in the cap, a resilient stopper, flanges on the stopper, the stopper being receivable in the cap and the extension with its flanges sprung over the undercut flanges, whereby to lock the cap to the extension. 70 75

In testimony whereof I have signed my name to this specification.

JOSE G. BOUFFARTIQUE.
